Inventor

United States Patent Office.

WILLIAM G. CREAMER, OF BROOKLYN, NEW YORK.

Letters Patent No. 73,509, dated January 21, 1868.

IMPROVED CAR-BRAKE.

The Schedule referred to in these Letters Patent and making part of the same.

TO ALL WHOM IT MAY CONCERN:

Be it known that I, WILLIAM G. CREAMER, of the city of Brooklyn, county of Kings, State of New York, have invented new and important Improvements in Brake-Operators; and I do hereby declare that the following is a full and exact description thereof, reference being had to the accompanying drawings, and to the letters of reference marked thereon.

The nature of my improvement consists in the attachment of a jointed pawl, with a lever-handle or its equivalent, to the arm that is keyed to the brake-shaft, and the attachment to the brake-operator, containing the spring that is used for applying the brakes, a circle of ratchet-teeth for retaining the momentum of the spring at the point of reaction.

The object of this improvement is to effect the instant release of the pressure of the brakes upon the wheels. As brake-operators are now constructed, some time is required to release the brakes after they have been applied, and it frequently requires the strength of two men, and thus an unnecessary detention of the train is caused.

To enable others skilled in the art to make and use my invention, I will proceed to describe its construction and operation.

I construct my brake-operator with a loose pulley, actuated by a weight or spring, or with a drum, containing a spiral spring, substantially as heretofore, and at the under side of the drum or pulley I attach a circle of ratchet-teeth, as shown at A A, Figures 1 and 2. In connection therewith is a pawl, B, as shown at figs. 1 and 2. At the extremity of the arm C, which is keyed firmly to the brake-shaft, I attach a jointed pawl, D, with a lever-handle, E, as shown at C, figs. 1 and 2, taking into a circle of ratchet-teeth in the top of the drum, in place of a plain pawl, as heretofore used.

Thus constructed, the operation of the brake-operator is as follows: The jointed pawl D, at the top of the drum, is in place, as shown. The side-jointed pawl G is also in place, as shown by the drawings. The side pawl B is turned outward, as shown by the dotted lines. The brakeman now takes hold of the hand-wheel F, and turns it from right to left, thus winding up the drum containing the spring. The side pawl G holds the power so gained. When the spring is fully wound up, the side pawl B is turned into the ratchet-teeth, as shown. It is now desired to apply the brakes by the brake-operator. The lever H is lifted upward, which disengages the pawl G, and instantly the power of the spring revolves the drum K and brake-shaft I, winding up a chain, (attached to the brake-levers,) which connects at the lower part of the brake-shaft at J. It is now desired to release the brakes, to accomplish which, lift the lever-handle E of the top pawl D, and the pressure on the point of it, where it engages the teeth, causes it to double up and assume the position shown by the dotted lines, and the brakes are instantly released from pressure on the wheels, by the backward movement of the brake-shaft, and at the same time the drum reacts, and the pawl B is released from pressure. This enables the car to proceed without delay. To reset the spring, put the top and side pawls D and G in the position shown, the side pawl B in the position shown by the dotted lines, fig. 2; then turn the hand-wheel F from right to left, and then wind up the spring with full force; then turn the side pawl B in against the teeth, and the brake-operator is ready for action.

What I claim as improvements in my automatic brake, are—

1. The jointed pawl D, in combination with the arm on the brake-shaft I, and the ratchet on the drum K, substantially as described and for the purposes set forth.
2. In combination with the drum and jointed pawl, as above claimed, I claim the ratchet-wheel A and pawl B, the wheel being fixed on the drum, as described, and for the purposes set forth.

WILLIAM G. CREAMER.
